UNITED STATES PATENT OFFICE.

WILLIAM A. COOPER, OF MONTREAL, QUEBEC, CANADA.

SLEEPING-CAR LADDER.

1,308,147.

Specification of Letters Patent.

Patented July 1, 1919.

Application filed February 19, 1917. Serial No. 149,513.

To all whom it may concern:

Be it known that I, WILLIAM A. COOPER, of the city of Montreal, Province of Quebec, Dominion of Canada, a subject of the King of Great Britain, have invented certain new and useful Improvements in Sleeping-Car Ladders; and I do hereby declare that the following is a full, clear, and exact description thereof.

- 10 My invention has for its object to provide a step-ladder of rigid straight form adapted for use as a means for reaching the upper berths in sleeping cars, and adapted to be folded in half to facilitate packing away.
- 15 The ladder consists of two sections pivoted together, and provided with locking means for maintaining the sections in alinement. The upper section may be swung down into the dotted line position, shown in Figure 1, 20 and used as a prop member, or it may be swung into contact with the lower section, when it is desired to economize space.

For full comprehension, however, of my invention reference must be had to the accompanying drawings forming part of this specification in which similar reference characters indicate the same parts, and wherein:

Fig. 1 is a perspective view of my improved ladder illustrating the positions in which it may be employed.

Fig. 2 is a detail fragmentary perspective view of the united ends of the ladder parts folded together, and illustrating the particular locking means;

Fig. 3 is a detail sectional view of a portion of the top of the lower part of the ladder and lower portion of the upper part with the lock shown in elevation;

Fig. 4 is a similar view to Fig. 3 taken at right angles thereto; and

Fig. 5 is a transverse vertical sectional view taken on line 5—5 Fig. 1 and illustrating particularly the joint between the ladder parts.

45 The parts of my improved ladder are illustrated at *b* and *c*, respectively, each part consisting of side bars with steps *d* equal in width to the width of the side bars and having cushion treads *e* and the parts being hinged together by strap hinges *F* extending along the side bars. The step *g* at the hinge connection of the parts is divided longitudinally substantially midway of its width and one half is carried by the lower part and the other by the upper part. The first-mentioned half is mounted upon the

upper ends of the side bars of the lower part and its ends project laterally beyond the side bars, the side bars of the upper part being cut as at *h* to afford clearance 60 when the parts are in alinement and the remaining portion *i* of the stiles carrying the other half of the step. A transverse reinforcing member is mounted upon the upper end of the lower part and is adapted 65 to reinforce the half of the step *g* carried by the part *c* when the parts are in alinement. This particular form of the upper part of the ladder provides a rigid connection between the two parts which relieves 70 the hinges and the locking means, about to be described, of practically all strain. A portion of one of the side bars of the upper part of the ladder which is adapted to rest upon the front half of the step *g* carries a 75 latch consisting of a resilient metal strip *k* having a lug *w* integral therewith on its lower end, the strip being fastened by screws or other suitable means to the side bar and guided by a collar *m*. The latch 80 head projects below the end of the side bar and is adapted to engage a latching plate *o* secured over a recess *p* in the step *g*. In order to facilitate the operation of the latch it is made with a bend *k¹* to serve as a 85 thumb-piece. The top of the upper part of the ladder has rotatably mounted therein a shaft *s* with a pair of integral hooks *t* located near opposite ends of the shaft and adapted to engage the edge of an upper 90 berth or any other fixed part upon which it is desired to support the ladder.

In order to prevent relative displacement of the ladder parts when the upper part is used as a prop a hook *u* is carried by the 95 rear edge of the step next to the top one of the lower part of the ladder and a pair of eyes *v* and *v¹* are carried by the back edge of the first step of the upper part.

When in use as a long ladder to enable 100 the upper berths to be reached the parts of the ladder are swung into alinement which causes them to be rigidly locked in this position and permits the ladder to be carried from berth to berth without danger of the 105 parts becoming disconnected, and I make the hooks *t* of sufficient length to have their hooked ends above the top of the ladder and therefore allow the top of the ladder to come below the edge of the berth and permit a 110 proportionately shorter ladder to be used. When it is desired to store the ladder away

the thumb-piece k^1 is pressed inwardly thus releasing the latch from the latching plate and freeing the parts of the ladder from each other and enabling them to be folded together. The hook u is then made to engage the eye v . To use the ladder as a short self-sustaining one, the top portion is swung to a position at an angle to the bottom portion and the hook engaged with eye v^1 which thus affords a rigid stay between the parts for preventing displacement.

What I claim is as follows:

10 A ladder divided substantially midway its length into two parts hingedly connected together, each part consisting of side bars and steps, the step at the hinge connection being divided longitudinally substantially

midway of its width, one half being carried by the lower part and the other by the upper, and means constructed and arranged to automatically rigidly lock the parts when brought into alignment, said means consisting of a plate rigidly carried by one part and a resilient member carried by the other part and having a lug on its lower end adapted to engage the said plate.

15 In testimony whereof I have signed my name to this specification in the presence of two witnesses.

W. A. COOPER.
